UNITED STATES PATENT OFFICE.

MORGAN COLT, OF NEW HOPE, PENNSYLVANIA.

DESIGN FOR A CHAIR OR THE LIKE.

Application filed March 12, 1926. Serial No. 16,900. Term of patent 7 years.

To all whom it may concern:

Be it known that I, MORGAN COLT, a citizen of the United States, and a resident of New Hope, in the county of Bucks and State of Pennsylvania, have invented a new, original, and ornamental Design for Chair or the like, of which the following is a specification, reference being had to the accompanying drawing, forming part thereof.

The figure is a view in elevation of a chair, showing my new design.

I claim:

The ornamental design for a chair or the like, as shown.

MORGAN COLT.
